Des. 232,559

Patented Aug. 27, 1974

232,559

MICROFICHE ENCODER OR THE LIKE

Andrew Virgil McClare, Rochester, N.Y., assignor to
Eastman Kodak Company, Rochester, N.Y.

Filed Jan. 22, 1972, Ser. No. 325,786

Term of patent 14 years

Int. Cl. D14—02

U.S. Cl. D26—5 C

FIG. 1

FIG. 2

FIG. 3

FIG.4

FIG.5

FIG.6

FIG. 1 is a top plan view of a microfiche encoder or the like showing my new design;
FIG. 2 is a front view thereof;
FIG. 3 is a bottom view thereof;
FIG. 4 is a right side view thereof; and
FIGS. 5 and 6 are rear and left side views respectively thereof.

I claim:
The ornamental design for a microfiche encoder or the like, as shown.
